VANE-TYPE ROTARY PUMPS

Emanuel S. Briscoe, Oklahoma City, Okla.

Application June 27, 1955, Serial No. 517,983

9 Claims. (Cl. 230—152)

This invention relates to pumps and more specifically to cooling, lubricating and sealing means for pumps such as, for example, reciprocating vane-type rotary pumps.

An important object of the invention is to depart from the method and means for introducing a liquid medium (as oil for cooling, lubricating and sealing) into a pump along with a fluid (as a gas, for refrigeration purposes) or as a mixture of liquid and gas mixed prior to introduction of the mixture into the pump, and employ, instead, means for introducing the liquid into the pump independently of the introduction of the fluid.

Another important object of the invention is to introduce a cooling, lubricating and sealing medium into a pump, through the shaft of the rotor thereof and conduct the medium through the shaft and outwardly thereof to cool, for example, both of two widely-spaced-apart bushings which provide bearings for the shaft.

Still another important object is to introduce the cooling, lubricating and sealing medium into a pump by way of the shaft of the rotor thereof and conduct it through the shaft in such a manner that the seal assembly, at the end of the pump housing where the shaft emerges therefrom, will be cooled.

Additionally, another important object is to provide for the introduction of a cooling, lubricating and sealing medium into a pump by way of the shaft of the rotor thereof and conduct the medium through the shaft from substantially end to end thereof within the pump and then discharge the medium exteriorly of the shaft for lubricating and sealing of portions thereof exteriorly of the shaft.

In addition, another important object is to provide for the introduction of a cooling, lubricating and sealing medium into a pump by way of the shaft of the rotor thereof and then conduct the medium through the shaft, longitudinally thereof, and then out of the shaft and into and out of the chamber of the pump containing the sealing assembly for the shaft, for cooling and lubricating that assembly.

Another important object is to provide for the cooling, lubricating and sealing of the vane-type rotary pumps of refrigerating systems, for example, brought about by introducing a pre-cooled cooling, lubricating and sealing medium into the shaft of the pump rotor and conduct it through the shaft, to cool the shaft bushings and then discharge the medium by centrifugal force, along the vanes of the pump to seal the spaces between the vanes and the support therefor as well as the spaces between the ends of the vanes and the wall of the stator chamber, as the medium is thrown, by centrifugal force, outwardly of the rotor and against the wall of the stator chamber.

Still another object is to provide a system for the introduction of a cooling, lubricating and sealing medium into the rotor of a vane-type rotary pump in which the vanes reciprocate in recesses, as distinguished from slots, and the medium further functions as cushioning means for the vanes.

Other objects and advantages of the invention will be

2

apparent during the course of the following detailed description of the invention, taken in connection with the accompanying drawings, forming portions of this disclosure, and in which drawings:

5 Fig. 1 is a transverse section, of one form of pump, embodying the invention, substantially on the line 1—1 of Fig. 2.

Fig. 2 is a longitudinal section of the pump of Fig. 1.

10 Fig. 3 is a fragmentary transverse section, substantially on the line 3—3 of Fig. 2.

Fig. 4 is a transverse section of a pump of a construction different from that of Figs. 1, 2 and 3 and embodying the invention.

15 Fig. 5 is a longitudinal section of the pump of Fig. 4, taken substantially on the line 5—5 of Fig. 4.

Fig. 6 is a transverse section of a pump of a construction different from those of Figs. 1 to 5 inclusive, and embodying the invention.

20 Fig. 7 is a longitudinal section of the pump of Fig. 6, taken substantially on the line 7—7 of Fig. 6.

Fig. 8 is a transverse section of a pump differing from those of Figures 1 to 7 inclusive, and embodying the invention.

25 Fig. 9 is a longitudinal section of the pump of Fig. 8, taken substantially on the line 9—9 of Fig. 8.

Fig. 10 is a plan of a bushing forming a portion of the pump of Figs. 8 and 9.

30 Fig. 11 is a section of the bushing of Fig. 10, substantially on the line 11—11 of Fig. 10.

Fig. 12 is a diagrammatic showing of one application of any of the pumps containing the invention.

In the drawings, wherein for the purpose of illustration are shown four pumps embodying the invention and wherein similar reference characters designate corresponding parts throughout the several views, the letters A, B, C and D designate generally the four pumps.

The pump A of Figures 1, 2 and 3 includes a stator having a housing 15 provided with suction or intake port 16 and exhaust port 17, for the fluid (as air, ammonia, dichlorodifluoromethane or monochlorodifluoromethane, generally known as Freon, and carbon dioxide) to be pumped, and opening into a pump chamber 18 within the housing and having an arcuate wall surface, faced by an arcuate liner 19, which may be a shell, with two spaced-apart flanged bushings 20 and 21 which face each other and abut the edges of the liner and provide rotor bearings. The bushing 20 extends to an end wall 22 of the housing and the bushing 21 separates the chamber 18 from a conventional rotor shaft seal assembly 23 contained within the chamber 24 of a cup like seal housing 25 carried by an end cap 26, which end cap is provided with screw threads mating with the housing 15 at the end thereof opposite the end wall 22.

55 Pivotedly carried by the stator is a rotor having outer hollow shaft portions 30 and 31 respectively which are preferably integral with an enlarged vane-carrying hollow body portion 32, with the latter intermediate the shaft portions and provided with a plurality of spaced-apart vane-receiving slots 33 extending from the hollow 34 of the body portion 32 to the periphery of the latter to slidably receive reciprocating "back up" vanes 35, which are adapted to abut each other at the center of the hollow body portion. The flanged bushings 20 and 21 abut the end faces 36 and 37 respectively of the body portion 32 and are widely spaced apart. By "widely" is meant that the inner faces of the two bushings 20 and 21 are spaced apart a shortest distance such as substantially eleven times the thickness of the wall of the bushing 20.

60 In the example shown in Fig. 1, the movement of the rotor is counterclockwise.

Means 40 to conduct a liquid (such as a lubricant oil or mixtures of lubricating oils) to the rotor may be a

conventional conduit 41 extending to a nipple 42 which projects through a suitable opening 43 in the end wall 22. The conduit 41 may be coupled to the nipple 42 as by a coupling nut 44 engaging a flared end of the conduit and in screw threaded engagement with the nipple.

Referring again to the rotor, means is provided therewith for the flow of the liquid from the means 40 through the rotor to that part of the shaft portion 31 within the chamber 24. This means includes the provision of a plurality of spaced-apart openings 46 in the shaft portion 30 each communicating with a separate longitudinally extending way 47 extending through the shaft portion 30, body portion 32 and shaft portion 31 quite close to the outer peripheries of the shaft portions rather than, as in many cases, through the center of a shaft portion. From this specific part of the shaft portion 31, the liquid flows into the hollow 37 of the shaft portion 31 by way of a plurality of spaced-apart openings 48 in the shaft portion 31, with these openings 48 disposed very close to the outer end of the chamber 24, whereby the liquid must flow through the shaft portion 32 to empty into the hollow 37 in a zone very close to this outer end. This will afford a decided cooling of the seal chamber 24 and its seal assembly 23 as well as of the adjacent bushing 21 before it reaches the slots 33. Similarly, the liquid within the openings 46 and adjacent portions of the ways 47 tend to cool the bushing 20. In order to block flow of liquid into or from the hollow 34 at the end thereof adjacent the end wall 22, I provide an imperforate closure or partition wall 49 across the hollow 34, and in order to block the flow of liquid into the hollow 37 outwardly beyond the housing 25, I provide an imperforate closure, baffle or partition wall 50 across the hollow 37. Preferably, these are disposed close to the openings 46 and 48 whereby the liquid will be baffled and will quickly enter these openings after it begins to flow toward the wall 22.

The liquid entering the hollow 37 will then flow therethrough and to the hollow 34 in the body portion 32 whereupon it will tend to flow outwardly by centrifugal force along the slots 33, in the spaces between the surfaces thereof and the surfaces of the vanes 35 and provide seals so that the fluid within the chamber 18 will not be able to enter these spaces. Moreover the liquid finding its way to the chamber surface films it and provides a seal between the outer ends of the vanes and this surface. Liquid, in excess of that utilized in film forming is drawn out via the exhaust port 17 to be subsequently separated from the fluid and returned for use, as will be subsequently explained.

A small opening 51 in the bushing 21 and disposed at the low pressure side of the pump, provides for communication between the chambers 18 and 24 whereby there will be a flow of a volume of the contents of chamber 18 into and out of the chamber 24 to aid in cooling the adjacent bushing 21 as well as the seal assembly 23. The flow into and out of the chamber 24 is brought about by the fluctuations of the pressure on the low-pressure side of the pump, caused by fluctuation of the heat load upon an expansion coil or the like to which the pump may be connected.

Referring now to the form of the invention embodied in the pump B of Figures 4 and 5, wherein the vanes do not back up as in the pump A but are slidably retained in slots extending to the hollow of the hollow body portion of the rotor.

The pump B includes a stator substantially like that of the stator of the pump A, whereby a chamber 55 is provided, in the housing 56 with intake or suction port 57 and exhaust port 58, and there is a rotor or shaft seal assembly 59 within a chamber 60 closed by a cap-like seal housing 61, opposite an end wall 62 of the housing 56 and carried by an end cap 62a substantially similar to and attached like the end cap 26. Flanged bushings 63

and 64, substantially like the bushings 20 and 21 are also preferably provided.

As for the rotor of the pump B, there are outer hollow shaft portions 65 and 66, preferably integrally connected to an intermediate hollow body portion 67 with the latter provided with a plurality of spaced-apart vane-receiving apertures 68 which may be slots extending from the hollow 69 in the body portion 67 to the outer periphery of the latter. The apertures 68 slidably retain vanes 70 and the hollow 69 continues through the shaft portions 65 and 66.

Means 80 to conduct a suitable liquid (as oil) to the rotor may be a conventional conduit 81 opening to the interior of a nipple 82 disposed in a suitable opening 83 in the end wall 62. The conduit 81 may be coupled to the nipple 82 as by a coupling nut 84 like the nut 44. Preferably this nipple is elongated within the hollow 69 to provide means to flow liquid through the rotor. This elongation is shown as a centrally-disposed way or tube 87, smaller in outer diameter than the diameter of the hollow 69, and which has its discharge mouth very closely adjacent the outer end of the chamber 60, whereby the liquid which flows through this way must empty into the hollow 69 in a zone closely adjacent this outer end. Thereupon the liquid flows along the wall of the hollow 69 to cool the chamber 60, seal assembly 59 and bushing 64 before it reaches the apertures 68, since it cannot flow farther in one direction because of the closure, baffle or partition wall 90 and it will reverse its flow in the new path toward the end wall 62.

After the liquid reaches the inner ends of the apertures 68 its action is similar to that described in connection with the pump A.

Of course some of the liquid will also cool the bushing 63, as is obvious.

A small opening 91 in the bushing 64 functions as does the opening 51 in the bushing 21.

Figs. 6 and 7 illustrate the pump C which is preferably provided with the stator housing 95 much like those of the pumps A and B, although the intake or suction port 96 and exhaust port 97 may have bevelled or funnelled inner end portions as is shown in Fig. 6, extending to the pump chamber 98. There are preferably provided the flanged bushings 100 and 101 and the housing 95 has an end wall 102 with a rotor seal assembly 103 at the opposite end of the housing contained in a chamber 104 closed by a seal housing 105. The seal housing 105 is carried by an end cap 106 substantially similar to the end caps 26 and 62a and attached to the housing 95.

The rotor of the pump C differs from those of the pumps A and B by having its vanes slidably disposed in recesses or pockets instead of slots.

This rotor includes outer hollow shaft portions 110 and 111 respectively, preferably integral with an intermediate hollow body portion 112 with the latter provided with aperture 113, which may be spaced-apart vane-receiving recesses or pockets. These recesses or pockets have their bottoms spaced from the hollow 114 in the body portion 112 and slidably receive the vanes 115.

Means 120 to conduct a liquid (as oil) to the rotor of the pump C may be similar to that employed in the pump B and include a conventional conduit 121 opening to and coupled by means of a coupling nut 121a to a nipple 122 carried by the wall 102, an opening therein being provided for the nipple, which latter is preferably elongated within the hollow 114 to provide means to flow liquid through the rotor. This elongation is shown as a centrally-disposed way or tube 127, smaller in exterior diameter than the diameter of the hollow 114, and which has its discharge mouth very closely adjacent the outer end of the chamber 104, whereby the liquid which flows through the way must empty into the hollow 114 in a zone closely adjacent this outer end. Thereupon the liquid flows along the wall of the hollow 114 to cool the chamber 104 and its seal assembly 103 and, subsequently,

the bushing 101 before it reaches a plurality of openings 128 to the bottoms of the vane-receiving apertures 113.

After the liquid reaches the bottoms of the apertures 113, its action is partly similar to that described in connection with the pump A. However, it will also provide seals between the bottoms of the apertures and the bottoms of the extended vanes.

Of course, as is clear, some of the liquid will also cool the bushing 100.

A closure, baffle or partition wall 130 closing the outer end of the shaft portion 111 prevents flow of liquid from this end and causes its return toward the end wall 102.

A small opening 131 in the bushing 101 functions like the opening 51 in the bushing 21.

In Figures 8, 9, 10 and 11 the pump D is illustrated. It is preferably provided with the stator housing 135 substantially like the housing 95 and having the intake or suction port 136 and exhaust port 137 extending to a pump chamber 138. Flanged bushings 140 and 141 are provided, but differ from the bushings 20, 21, 63, 64, 101 and 102 in that each contains a portion of the means for flow of liquid through the rotor and this will be subsequently described. There are a rotor seal assembly 143, a chamber 144 therefor and a housing 145 containing the chamber and assembly and contained within an end cap 146 substantially like the end cap 26 and similarly attached.

The rotor of the pump D has some of the features of the rotor of the pump C in that the vanes are slidably disposed in apertures 153, as recesses or pockets but the flow of liquid from the hollow of the rotor shaft to the exterior of the rotor is different.

This rotor includes outer hollow shaft portions 150 and 151 respectively, preferably integrally connected with an intermediate hollow body portion 152 with the latter provided with the spaced-apart vane-receiving apertures 153, having their bottoms spaced from the hollow 154 of the body portion, and slidably receive the vanes 155.

Means 160 to conduct a liquid (as oil) to the rotor of the pump D may be similar to that employed in the pumps B and C and include a conventional conduit 161 connected as by a coupling nut 161^a to a nipple 162 extending through a suitable opening in the wall 142. The nipple is preferably elongated within the hollow 154 to provide means to flow liquid through the rotor. This elongation is shown as a centrally-disposed way or tube 167 smaller in outer diameter than the diameter of the hollow 154 and which has its discharge mouth very closely adjacent the outer end of the chamber 144, whereby the liquid which flows through the way must empty into the hollow in a zone closely adjacent this outer end. Thereupon the liquid flows along the wall of the hollow 154 so as to cool the bushing 141 and enters, a plurality of openings 168 in the shaft portion 151, closely adjacent its juncture with the hollow body portion 152, whereupon it flows through an opening 169 in the bushing 141 which opening may be provided by beveling the vertical face of the bushing at the juncture of the flanged portion and this vertical face. This opening 169 extends substantially 180° and is adapted to front at the intake portion of the chamber 138. Openings 170, similar to the openings 168, are provided in the shaft portion 150 adjacent its juncture with the hollow body portion 152 and communicate with an opening 171, substantially like the opening 169, in the bushing 140.

It is now clear, in Fig. 9, that the liquid provides a cushion behind the vanes 155 which tends to press the outer edges of the extended vanes firmly against the wall of the chamber 138, and this liquid may flow along the spaces between the extended vanes 155 and the surfaces of their recesses 153, and will discharge, by centrifugal force into the suction portion of the chamber 138 to be carried through the chamber, providing a seal, and to be

then discharged from the chamber through the exhaust port 137.

A small opening 173 in the bushing 141 is provided to function as do the openings 51, 91 and 131.

In order to prevent flow of liquid much beyond the outer end of the way 167, I prefer to provide the closure or partition wall 174 which functions as does the walls 50, 90 and 130.

Fig. 12 illustrates one application of any of the pumps A, B, C or D, and therein designated as "pump." There the pump is connected, at its exhaust port (which may be any of ports 17, 58, 97 or 137) with a suitable conduit 175 opening into a conventional separator 176 for liquids, as a lubricating oil, and fluids, such as compressed refrigerant, with the separator containing, for example, copper wool 177 to provide anti-splash means for the oil separated and to prevent its entry into the separated compressed refrigerant conduit 178. The separated oil flows through the conduit 179 where it may be conventionally cooled, as by an air blast upon the coils 180 and then flows through a conduit which may be any one of conduits 41, 81, 121 or 161 to the rotor of the pump as has been described. From the conduit 178 the compressed refrigerant flows to and through a conventional condenser 181 and evaporator 182 with a conventional expansion valve between them, and from the evaporator the refrigerant flows through the suction conduit 183 to the suction or intake port of the pump.

Each form of the invention, adapted to vane-type rotary pumps of different build, includes means for introducing a mobile cooling, lubricating and sealing medium into the pump by way of the shaft of the rotor thereof to cool all the bushings surrounding the shaft, since the medium flows from one end of the shaft to the other end thereof within the housing of the pump, is then baffled to flow in an opposite path, and finds its way by suction and centrifugal force between the surfaces of the vanes and the apertures (slots or recesses) in the rotor body, to be thrown by centrifugal force upon the surface of the stator chamber, with a small volume of the medium being alternately forced into and sucked out of the rotor seal chamber through one of the bushings at a location at the low-pressure side of the pump. Each utilizes a hollow shaft of initially conventional form, modified to embody features of the invention. In the recess type forms C and D the medium tends to provide a cushion behind the extended vanes so as to cause these vanes to press firmly against the walls of the chambers to aid in sealing.

Various changes may be made to the forms of the invention herein shown and described without departing from the spirit of the invention or scope of the claims.

What is claimed is:

1. A reciprocating-vanes rotary pump having an elongated housing provided with opposite end walls and a rotor chamber; a vanes-carrying partially hollow rotor body within said chamber; a hollow rotor shaft rigid with and supporting said body; spaced-apart bushings providing bearings for said shaft and being carried by said housing;
2. a rotor shaft seal assembly disposed about said shaft, carried by said housing adjacent one of said end walls and one of said bearings and open to said chamber; introducing means extending through the other of said end walls to introduce a flowable cooling, lubricating and sealing medium into said shaft at the longitudinal axis of said shaft and having a discharge mouth within said shaft and spaced from the tubular wall of said shaft; baffle means closely adjacent and facing said mouth and disposed across the hollow of said shaft, to change the direction of flow of said medium; said shaft being provided with a plurality of passageways to conduct said medium from said baffle means, first radially and then longitudinally of said shaft, to lubricate and cool said bearings and seal assembly; and discharge means carried by said rotor body to continuously cause a volume of said medium from

said passageways to contact the surfaces of the vanes of said pump, when said rotor body is in rotation, and be discharged outwardly of said body by centrifugal force to lubricate the wall of said chamber.

2. A reciprocating-vanes rotary pump according to claim 1 characterized in that one of said bearings is provided with an intake passageway extending therethrough from said chamber directly to said seal assembly.

3. A reciprocating-vanes rotary pump according to claim 1 characterized in that one of said bearings is provided with an intake passageway extending substantially parallel with said longitudinal axis and through said one of said bearings from said chamber directly to said seal assembly, said intake passageway having an intake port with the port alternately opened and closed by said vanes when said rotor body is in operation.

4. A reciprocating-vanes rotary pump according to claim 1 characterized in that said rotor body is provided with a plurality of spaced-apart apertures extending to the hollow thereof and to the outer periphery thereof with vanes slideable within said apertures and with the inner ends of said vanes constructed and arranged to abut one another, and said passageways are disposed inwardly of both the outer peripheries of said shaft and rotor body.

5. A reciprocating-vanes rotary pump according to claim 1 characterized in that said rotor body is provided with a plurality of spaced-apart apertures extending to the hollow thereof and to the outer periphery thereof, with vanes slideable within said apertures and with the inner ends of said vanes extending to the inner periphery of said rotor body, and said introducing means includes a nipple extending into said other of said ends, and said passageways include a tube extending from said nipple through said shaft and body and the outer periphery of said tube is spaced from the walls of said shaft and rotor body and said inner ends of said vanes.

6. A reciprocating-vanes rotary pump according to claim 1 characterized in that introducing means includes a nipple extending into said other of said ends, and said passageways include a tube extending from said nipple through said shaft and body and the outer periphery of said tube is spaced from the walls of said shaft and rotor body and said inner ends of said vanes, said rotor body is provided with a plurality of spaced-apart apertures, extending to the outer periphery and toward the inner periphery of said rotor body and are substantially alike, with pump vanes slideable within said apertures and said apertures are spaced from said tube.

7. A reciprocating-vanes rotary pump according to claim 1 characterized in that said rotor body is provided with a plurality of spaced-apart apertures, extending to the outer periphery of said rotor body, and having inner ends with vanes slideable within said apertures, introducing means includes a nipple extending into said other of said ends, and said passageways include a tube extending from said nipple through said shaft and body and the outer periphery of said tube is spaced from the walls of said shaft and rotor body and said inner ends of said vanes, and said discharge means defines a plurality of openings in said hollow body which extend from said hollow thereof to the inner ends of said apertures, and are spaced from said tube.

8. A reciprocating-vanes rotary pump according to claim 1 characterized in that said partially hollow rotor body is provided with a plurality of spaced-apart apertures extending to the outer periphery of said partially hollow rotor body, with pump vanes slideable within said apertures, and said discharge means defines a plurality of openings in said partially hollow rotor body extending from the hollow thereof to said bushings and openings in said bushings in communication with said apertures upon rotation of said partially hollow rotor body.

9. A reciprocating-vanes rotary pump according to claim 5 characterized in that said bushings have faces facing the chamber of said housing and with said partially hollow rotor body in rotative contact with said faces, and said discharge means defines an arcuate opening in each of said faces of said bushings, and a plurality of openings in said hollow body extending from the hollow thereof to the arcuate openings in the faces of said bushings, and said arcuate openings are in communication with said apertures upon rotation of said partially hollow rotor body and are spaced from said tube.
